UNITED STATES PATENT OFFICE.

CHARLES M. MANLY, OF BROOKLYN, NEW YORK.

COLLAR.

1,187,638.

Specification of Letters Patent. Patented June 20, 1916.

Application filed February 4, 1911. Serial No. 806,817.

To all whom it may concern:

Be it known that I, CHARLES M. MANLY, a citizen of the United States, residing at No. 113 Montague street, Brooklyn, in the 5 county of Kings and State of New York, have invented a new and useful Collar, of which the following is a specification.

My invention relates to collars and more particularly to that class of collars which 10 form separate articles of manufacture and sale and in use are attached to the shirt or other garment in connection with which they are worn.

The object of my invention is to provide 15 a collar having a shirt engaging device for attaching the same at the back to the neck band of a shirt so that the collar button ordinarily used for that purpose may be dispensed with.

20 A further object of the invention is to so construct the fastening means that a collar button may be used therewith if desired or the button alone may be used without interfering with the comfort and appearance 25 of the collar.

In the accompanying drawings and annexed specification I have disclosed a preferred form of my improved collar, and in the said drawings, Figure 1 is a perspective view of said collar attached at the back to the neck band of the shirt, and Fig. 2 is a perspective view partly in section of the collar unattached.

30 Referring to the drawings, in which like reference characters refer to like parts in both views, 1 indicates the body portion of the collar, here shown as of the so-called "turned down" type and having the usual front button holes 2 and rear button hole 3 for attachment to the front and rear collar buttons. On each side of the rear button hole 3 the collar is provided with a band engaging member 4 here shown as consisting of a tab extending from the 40 lower edge of the collar and integral therewith and extending upwardly parallel

with the body of the collar. The tabs are to be laundered stiff like the collar so as to maintain their position relative thereto.

In use the collar is attached to the shirt 50 by hooking the tabs under the outer portion of the neck band 5 at the back of the shirt where the band is formed with a pocket to receive the collar button as indicated at 6 in dotted lines in Fig. 1, and then bringing 55 the ends around and buttoning them to the front collar button 7.

A collar fastened with a button at the rear is frequently very uncomfortable for the reason that the button must be thicker by 60 at least the thickness of the base and head than the material of the shirt and collar and is therefore pressed into the neck by the other garments, and in the case of a turned down collar, by the outer ply of the collar. 65 Further, the collar button is so positioned that it comes against the vertebra at the base of the neck where its pressure and rubbing are most liable to make a sore. With my improved collar the additional 70 thickness occasioned by the tabs is scarcely perceptible and the tabs are arranged at either side of the middle so as not to come in contact with the vertebra.

I have shown my invention as applied to 75 a collar of the "turned down" type but it is obvious that any style collar may be formed in like manner.

I claim—

As a new article of manufacture, a collar 80 having a tab projecting from the lower edge of the collar at either side of the rear button hole, and spaced apart so that the outer edges of the tabs are a distance apart substantially equal to the length of the usual 85 collar button pocket in the rear of the neck-band of a shirt.

CHARLES M. MANLY.
